UNITED STATES PATENT OFFICE.

FRANCIS A. PETER, OF NEWSIDE, PENNSYLVANIA.

SNOW GUARD OR FENDER FOR ROOFS.

No. 884,850.

Specification of Letters Patent.

Patented April 14, 1908.

Application filed December 6, 1907. Serial No. 405,320.

To all whom it may concern:

Be it known that I, FRANCIS A. PETER, of Newside, Washington township, in the county of Lehigh and State of Pennsylvania, have invented certain new and useful Improvements in Snow Guards or Fenders for Roofs; and I hereby declare that the following is a full, clear, and exact description thereof, reference being had to the accompanying drawings, which form a part of this specification.

This invention is an improved snow-guard or holder especially adapted for use on tin roofs having standing seams, and its object is to provide a guard which can be readily attached to such roofs without perforating or puncturing the tin, or the seam.

The invention will be clearly understood from the following description of the guard illustrated in the accompanying drawings, in which

Figure 1 is a top plan view of the guard. Fig. 2 is a side view thereof partly broken. Fig. 3 is a front view thereof. Fig. 4 is a vertical section on line 4—4, Fig. 1. Fig. 5 is a horizontal section on line 5—5, Fig. 2; and Fig. 6 is a section on line 6—6, Fig. 2.

The guard comprises a clamping-member adapted to be fastened to one of the seams, or flanges on the roof; and a holding-member removably attached to the clamping-member.

The clamping-member is composed of similar but opposed plates 1, 1, which are preferably cast, provided with clamping ridges 1^a on their lower edges and opposed faces, between which edges the seam or flange S of the roof-tin is embraced; and above the seam the plates are perforated as at 1^b for the passage of a fastening bolt 2, provided with a nut 2^a by which the plates are tightly clamped upon and to the seam or flange S by which the sheets of tin forming the roof are united in the usual manner. The bolt 2 it will be seen comes above the flange S so that the latter is not injured by attaching the guard thereto.

The plates 1 may be longitudinally grooved as at 1^c just above the clamping edges 1^a, as shown. They may also be provided with laterally projecting flanges 1^d which will prevent the guard tilting or bending the seam S. The plates are also provided with tapered recesses 1^e on their outer faces, said recesses lying opposite and adjacent to each other, and forming a seat for the holding-member or snow arresting part 3 of the guard, which

member is preferably of cast metal, and approximately semi-circular in contour, but can be made ornamental in form as shown, and is adapted to stand cross-wise of or straddle the holding member, as shown. The holding member 3 has a tapered recess or notch 3^a adapted to fit upon the grooved portions 1^e of the clamping member, as shown in Figs. 3, 5, 6, and when the holding member is in place the inclined sides 3^b of the recess 3^a, impinge against the oppositely inclined bottoms 1^f of the grooves 1^e, and thus the holding member tends to clamp the plates 1, together and upon the seam or flange S; while said holding-member is in turn upheld by the walls of the recesses 1^e, see Figs. 5 and 6. The parts of plates 1 through which bolt 2 passes are preferably higher than the front parts of the plates, as shown at 1^h, so that the holding-member 3 is firmly braced against the snow pressure by the parts 1^h. When the detaining member is thus fitted to the clamping-member, it would secure the latter to the seam S, should bolt 2 work loose or be removed. I prefer however to use the bolt 2.

It will be seen that the holding-member extends on each side of the seam. In practice a row of such guards are attached to the seams across the length or width of the roof, and will effectually prevent the snow sliding in mass off the roof.

While especially designed for tin-roofs, the guards can be attached to other roofs having flanges or devices to which the plates 1 can be attached.

Having described my invention what I claim as new and desire to secure by Letters Patent is:

1. A detachable snow-guard for roofs comprising a clamping-member and a holding-member, said clamping-member being fastened to the roof and having adjacent recesses in its opposite sides provided with inclined bottoms, and a holding-member having a notch adapted to straddle the clamping-member and engage the recesses thereof, the inclined sides of the notch engaging the inclined bottoms of the recesses in the clamping-member, substantially as described.

2. In a snow-guard, the combination of a clamping - member composed of opposite plates adapted to engage opposite sides of a roof seam or flange and clamp it, and formed with adjacent recesses in their outer faces; with a holding-member arranged transversely

of the clamping-member and having a notch in its lower edge adapted to engage the recesses in the clamping-member, substantially as set forth.

3. The herein described snow-guard for roofs having standing seams or flanges, and the like, consisting of a two-piece clamping-member composed of similar opposite plates located on opposite sides of the seam, and 10 having clamping ridges on their lower edges and adjacent recesses in their outer faces;

and a holding-member straddling the clamping-member and having a tapered notch engaging the recesses in the plate, substantially as described.

In testimony that I claim the foregoing as my own, I affix my signature in presence of two witnesses.

FRANCIS A. PETER.
